UNITED STATES PATENT OFFICE.

JEFFERSON CAYLOR, OF INDIANAPOLIS, INDIANA, ASSIGNOR TO GENERAL BOX COMPANY, OF CHICAGO, ILLINOIS, A CORPORATION OF DELAWARE.

BOX.

Application filed June 30, 1923. Serial No. 642,734.

This invention relates to boxes, and more particularly to wirebound and similar boxes for shipping purposes.

Among other objects, the invention is intended to provide a plural-lidded box of light and strong construction.

The invention will be understood by reference to the annexed drawings in which:

Fig. 1 is a perspective view of a box embodying the invention, shown in open condition and with one of its heads removed.

Fig. 2 is a perspective view of the head omitted from Fig. 1.

Fig. 3 is a perspective view of the completed box in condition for shipment of contents.

The illustrative box comprises a wirebound blank folded about end sections or heads.

The folded blank in this instance comprises five sections, 1, 2, 3, 4 and 5, of which the intermediate sections 2, 3, 4 form the back, bottom and front of the box, while the sections 1 and 5 form a lid composed of oppositely opening parts.

These sections consist of suitable side material, such for instance as wood veneer attached to end cleats 6, 7, 8, 9 and 10 respectively, and the said sections including the cleats are connected in cooperative foldable relationship by binding wires 13, certain of which wires are stapled through the side material into the cleats. In folding the sections into the form which they occupy in the completed box, the end cleats will mate, in this instance with abutting ends, and the wires may be tensioned over the dihedral corners of the box. When the box is closed and the continuity of its bindings completed by fastening or tying the extremities of the binding wires as indicated at 14 in Fig. 3, the cleats form approximately rigid cleat frames around the ends of the box, resisting the tension of the wire bindings and cooperating with said bindings to maintain the form and integrity of the box as will be well understood by those familiar with the art.

The heads or end sections of the box are indicated by the numerals 11 and 12 in the drawings.

The form of box illustrated is adapted for shipment of objects such for example as cash registers, typewriting machines, and the like. For this purpose the box is constructed higher at the back than at the front, and with a

sloping lid section 5 extending from the relatively low front section 4 to a relatively narrow top section 1 adjacent the back section 2.

The heads 11 and 12 are shaped to correspond to the contour of the box, and are fitted within the sections 2, 3 and 4 and secured to the inner faces of the cleats 7, 8 and 9 of said sections by fastenings driven from the interior of the box. These sections 2, 3 and 4 and the heads 11 and 12 thus form an open topped container shaped to receive the article intended for shipment, such as a cash register; the integrity of such container being maintained by the securement of the cleats of the foldable sections to the end sections or heads.

After the cash register or other article for shipment is fitted within the box, the lid sections 1 and 5 are closed and secured by tensioning and twisting or otherwise fastening the terminal ends of the wire bindings; and the cleats of said lid sections are then secured to the corresponding margins of the heads 11 and 12, which are constructed to permit such attachment by fastenings driven externally of the box.

Thus the box in condition for shipment has all of its cleated sections, including the oppositely opening lid sections, firmly tied together by the heads of the box, as well as by the binding wires, and the opposite heads tied together at all sides by the cleated sections, making a strong and rigid package.

For lightness and strength of construction the heads 11 and 12 may consist of sheets of thin rigidifying material, such as sheet metal, which combines the advantages of adequate stiffness with capacity to flex under strains and to bend under such severe stresses as would disrupt wooden or other frangible heads. Such heads are relatively light in themselves and also occupy such slight space in the ends of the box as to reduce the length of wooden sections required for a box of given capacity, thus further importantly contributing to lightness of construction.

By securing the margins of sheet metal heads to the cleat frames all around, the cleats are thus metallically reinforced, permitting the use of smaller cleats than would be otherwise required, and again contributing to lightness of construction. At the same time the heads stiffen the box and co-operate with the wire bindings in flexibly

resisting distortive strains and in tending to restore the elements to original condition after a relative flexing under such strains.

The heads 11 and 12 are shown formed with outwardly extending flanges 15, 16, 17 and 18, providing angle reinforcement and serving as attaching flanges for securing the cleats of the lid sections to the heads. The flanges of each head, for instance the flanges 15 and 16 of the head 11, may be formed by striking up portions of the head, and are so related that they lie in different planes intersecting the main plane of the head at the point 20. Similarly, the planes of the flanges 17 and 18 of the head 12 intersect the main plane of the head at the corresponding point 19. Thus, the heads are so formed and so related to the lid sections 1 and 5 as to effectively supplement the binding force of the wires 13 to maintain an adequate closure for the box.

The upper marginal portions of the heads 11 and 12 are thus strengthened by reason of the angle reinforcement provided by these flanges, and the points of juncture of these strengthened portions at the points 19 and 20 constitute substantially the points of maximum strength of the head sections. These points of maximum strength of the heads are substantially coincident with the line of minimum strength of the cover, the latter line being determined by the points of contact of the lid sections 1 and 5 when they are placed in box closing position.

For further stiffening and strengthening effect, the metal heads may be suitably corrugated or provided with stamped ribs to form braces, struts, or the like, one appropriate form of corrugated head for a box of the illustrative form being shown, providing stiffening ribs 21 and 22.

It will be understood that the present invention is not limited to the specific details of construction of the illustrative box since such details may be variously modified to suit the different forms and dimensions of boxes required for different shipping purposes.

Claims covering the illustrative structure

are made in applications for sheet metal headed wirebound boxes filed by the present inventor June 2, 1923, and June 30, 1923, Ser. No. 643,010 and Ser. No. 648,733 respectively.

Having described my invention, I claim:—

1. A box adapted for the shipment of cash registers or similar articles, composed of folded cleated sections united by binding means; and five sided heads of thin stiff resilient material enfolded by the sections; the three intermediate folded sections constituting the opposite sides and bottom of said box and the other two sections constituting oppositely opening lid members of the box; said heads having flanges to which said lid sections are securable by fastenings driven externally of the box.

2. A box of the class described comprising, in combination, sheet metal heads having flanges along meeting edges; and foldable cleated sections arranged around said heads and having each of the cleats of the sections secured to said heads; certain of said cleats being attached to said flanges by fastenings driven externally of the box.

3. A box of the class described comprising, in combination, foldably connected cleated box sections co-operable to form cleat frames at the ends of the box; a plurality of the sections acting as a cover for the box; and heads cooperating with the box sections and having flanges along their edges adapted to cooperate with the lid sections; said flanges extending within the respective cleat frames and arranged so as to be readily secured to the cleats of the lid sections from the exterior of the box.

4. A box of the class described comprising, in combination, foldably connected cleated box sections cooperable to form cleat frames at the end of the box; heads cooperating with said sections, said heads having trihedral portions the apices of which are arranged within vertices of the cleat frames for bracing adjacent cleats.

In testimony whereof, I have signed my name to this specification.

JEFFERSON CAYLOR.
